UNITED STATES PATENT OFFICE.

WICK HATHAWAY, OF MADISON, OHIO.

DESIGN FOR A PAPER-CUTTER.

SPECIFICATION forming part of Design No. 33,150, dated September 4, 1900.

Application filed June 11, 1900. Serial No. 19,963. Term of patent 34 years.

To all whom it may concern:

Be it known that I, WICK HATHAWAY, a citizen of the United States, residing at Madison, in the county of Lake and State of Ohio, have invented and produced a new and useful Design for Paper-Cutters, of which the following is a specification.

This invention relates to a new and useful design for paper-cutters.

10 In the accompanying drawings, Figure 1 is a plan view. Fig. 2 is an edge view. Fig. 3 is an end view.

Referring to said figures by numerals of reference, 1 is a round disk-like head, from 15 the center of which extends a cylindrical portion 2, notched upon opposite sides, as at 3. Said cylindrical portion is gradually flattened

and broadened, as shown at 4, and merges into the paper-cutter, with which it is formed. This paper-cutter has a tapered end 6 and a convex edge 7, which is sharper than the opposite concave edge 8 thereof.

Having thus fully described my invention, what is claimed and desired to be secured by Design Letters Patent, is—

25 The design for a paper-cutter, substantially as herein shown and described.

In testimony whereof I affix my signature in presence of two witnesses.

WICK HATHAWAY.

Witnesses:

SETH MARSH,
C. W. GEURING.
